UNITED STATES PATENT OFFICE.

CHARLES H. WILKINS, OF NORFOLK, VIRGINIA.

DESIGN FOR A BADGE.

No. 38,313.

Specification for Design.

Patented Nov. 20, 1906.

Application filed October 26, 1906. Serial No. 340,781. Term of patent 3½ years.

To all whom it may concern:

Be it known that I, CHARLES H. WILKINS, a citizen of the United States, residing at Norfolk, in the county of Norfolk and State of Virginia, have invented a certain new, original, and ornamental Design for a Badge, shown in the accompanying drawing, which shows a front view.

I claim—
The ornamental design for a badge as shown.

CHAS. H. WILKINS.

Witnesses:

WALTER B. BURROW,
A. F. ROUX.
